(57) **CLAIM**

The ornamental design for a pillowcase, as shown and described.

DESCRIPTION

FIG. 1 is a front perspective view of a pillowcase shown in accordance with my new design;

FIG. 2 is a rear perspective view of the pillowcase shown in FIG. 1;

FIG. 3 is a front elevation view of the pillowcase shown in FIG. 1;

FIG. 4 is a rear elevation view of the pillowcase shown in FIG. 1;

FIG. 5 is a left side elevation view of the pillowcase shown in FIG. 1;

FIG. 6 is a right side elevation view of the pillowcase shown in FIG. 1;

FIG. 7 is a top plan view of the pillowcase shown in FIGS. 1; and

FIG. 8 is a bottom plan view of the pillowcase shown in FIG. 1;

FIG. 9 is a front perspective view of a pillowcase shown in accordance with my new design;

FIG. 10 is a rear perspective view of the pillowcase shown in FIG. 9;

FIG. 11 is a front elevation view of the pillowcase shown in FIG. 9;

FIG. 12 is a rear elevation view of the pillowcase shown in FIG. 9;

FIG. 13 is a left side elevation view of the pillowcase shown in FIG. 9;

FIG. 14 is a right side elevation view of the pillowcase shown in FIG. 9;

FIG. 15 is a top plan view of the pillowcase shown in FIGS. 9; and,

FIG. 16 is a bottom plan view of the pillowcase shown in FIG. 9.

The features shown in broken lines are for the purposes of showing portions of the pillowcase that form no part of the claimed design.
